CLOSURE

Raymond C. Pratt, Chicago, Ill.

Application November 1, 1941, Serial No. 417,448

9 Claims. (Cl. 160—265)

This invention relates to closure structures, particularly of the type wherein a slidable closure member is adapted to be moved or drawn across an opening, whereby to close or partially close the opening for the desired purpose.

It is an object of the invention to provide a closure structure of the type stated which is of improved construction, durability and operating characteristics.

More specifically, one of the objects of the invention is to provide a closure structure wherein the closure member may be operated to the desired position without the manipulation of lever controls or the like, and merely by the application of a suitable operating force to the closure member, at any place along the length thereof; and wherein the closure member, upon adjustment, exhibits a uniform predetermined resistance to movement and automatically stops upon the release of the operating force in adjusted position, and is thereafter maintained in adjusted position, exhibiting no tendency to creep or move from the position of adjustment even though subjected to protracted vibration.

A further object of the invention is to provide a closure structure wherein a predetermined tension is applied to the closure member to hold the same in taut and proper position, which tension is substantially uniform in all positions of closure member adjustment, and which tension prevents the closure member from sagging, wrinkling or becoming otherwise distorted or improperly positioned.

A still further object of the invention is to provide, in a closure structure of the type stated, improved guide means for guiding the closure member in its slidable movements, which guide means is self-aligning, precluding tilting or jamming of the parts or movement of the cooperating guide elements from predetermined position, whereby to insure smooth and efficient operation of the structure, as well as to preclude rattling, and also insure the provision of a light-tight structure.

Another object of the invention is to provide a closure structure of the type defined wherein the closure member and associated parts are provided as a self-contained unit or frame, which may be removably associated with a suitable supporting structure whereby to facilitate assembly, replacement and repair.

Still another object of the invention is to provide in a construction of the type stated, improved means for effecting automatic cleaning of the more inaccessible parts of the structure.

Various other objects, advantages and features of the invention will be apparent from the following specification when taken in connection with the accompanying drawings wherein certain preferred embodiments of the invention are set forth for purposes of illustration.

In the drawings, wherein like reference numerals refer to like parts throughout:

Fig. 1 is a general assembly view, in perspective, 10 of a closure structure as constructed in accordance with one preferred embodiment of the invention;

Fig. 2 is a similar view of a closure structure of modified form;

Figs. 3, 4 and 5 are detail perspective views, on an enlarged scale and specifically of the structure of Fig. 1; Figs. 3 and 4 illustrating the upper and lower portions, respectively, of one of the side guiding columns, and Fig. 5 illustrating the automatic wiper unit;

Fig. 6 is a front sectional view of the structure of Fig. 1, on an enlarged scale;

Figs. 7 and 8 are side sectional views of the structure, on the lines 7—7 and 8—8, respectively, of Fig. 6;

Fig. 9 is a partial, horizontal, sectional view through one of the side guiding columns and associated parts, on the line 9—9 of Fig. 6; and

Figs. 10 to 14 inclusive are detail perspective 30 views illustrating parts of the structure, Figs. 10 and 11 showing one of the tape rollers and the shade roller disc, respectively; Fig. 12 illustrating the method of anchoring the end of the shade or closure member upon the shade roller or cylinder;

Fig. 13 illustrating the slidable guide member forming a part of the guiding means, and Fig. 14 showing the friction shoe associated with the slidable guide member.

In the drawings, the particular closure structure set forth in detail for illustrative purposes 40 comprises a window shade structure, for example of a type for use on railway cars and the like, as certain features of the invention are particularly adapted for installations of this character. It is

45 to be understood, however, that the principles of the invention are adapted for closures generally, wherein an opening is to be closed or partially closed for whatever suitable or desired purpose. For example, in Fig. 2 a structure is illustrated 50 wherein a pair of closure members 10 and 11 may be horizontally drawn toward or away from each other, whereby to form a horizontally slidable closure panel for an opening in a wall structure 13.

55 Referring more specifically to the drawings.

and to the embodiment illustrated in Figs. 1 and 3 to 14 inclusive, it will be seen that the structure illustrated comprises a closure member, specifically a window shade 15, Fig. 1, and a frame, generally indicated by the numeral 16, adapted to be associated with the wall 17, which, as stated, may be the wall of a railway car or the like. Referring to Fig. 6, the wall 17 is provided with a bottom member 18, and a pair of upstanding side members 19 and 20, which together define the wall opening into which the closure frame 16 is insertable. The frame 16 comprises in general a pair of side guide columns 21 and 22, Fig. 1, a top or roller frame 23, and a bottom or sill frame 24.

The details of the frame elements are best shown in Figs. 3, 4 and 6, and are also illustrated in Figs. 7, 8 and 9. As shown, the left side guide column 22 comprises a pair of upstanding column members 26 and 27, preferably of wood or the like, encased in an outer sheet metal facing piece 28 and a pair of inner sheet metal facing pieces 29, 30, the facing pieces being secured to the column members in any desired manner, for example by means of screws or the like as indicated at 31 and 32, Fig. 4. The column members and the facing pieces cooperate to form a slot or opening 33 of general T-shape extending lengthwise of the column.

As best shown in Figs. 3 and 6, the outer wall of the outer facing piece 28 extends upwardly beyond the ends of the column members 26 and 27, and is secured by means of bolts 35, Fig. 6, to the depending flange 36 of a U-shaped frame piece 37 extending across the frame and forming the top member for the upper roller frame structure. The bolts 35 not only secure parts 28 and 36 together, but also in cooperation with a lower bolt 38 and suitable spacer members, provide means for securing the shade frame to the wall member 20.

In addition to the top piece 37, the roller frame 23 comprises a bottom member 40, Fig. 3, and front and rear members 41 and 42, the parts 37, 40, 41 and 42 cooperating to form a box-like frame structure within which the shade roller is rotatably mounted. The bottom member 40 is provided with a slot 43 extending lengthwise thereof, this slot being of T-shape at either end and aligned with the similarly shaped slots or openings in the columns. To facilitate the mounting of the shade roller within the roller frame, the top piece end flange 36 is struck inwardly as best shown in Fig. 3, and provided with a downwardly inclined slot 45 into which the shade roller may be inserted upon removal of the front plate 41 of the roller frame.

As best shown in Figs. 4 and 6, it will be seen that the outer side or wall of the facing member 28 also extends downwardly beyond the lower ends of the columns 26 and 27, whereby to be secured to the bifurcated end portions 47 and 48 of the sill frame 24. This sill frame, as illustrated, may comprise a main body 49 of wood or the like, suitably faced with sheet metal as indicated at 50. A U-shaped bracket 51 is secured to the facing member 28 by means of a bolt 52, Fig. 6, this bracket being adapted to lie between the bifurcated ends 47 and 48 of the sill frame, and forming a bearing support for a roller 53, the purpose of which will be later described. The bifurcated ends of the sill are secured to the column members 26 and 27 by suitable bolts as will be best seen by reference to Fig. 7.

The structure of the right column of the shade frame 16 is the same as that for the left column, the outer facing member for the right column, corresponding to the left column member 28, being indicated by the reference numeral 54 in Fig. 6. To close the openings between the sides of the shade frame 16 and the walls 19 and 20, facing pieces 55 and 56 are provided, Figs. 1 and 9.

It will be seen that the entire frame structure 16, including the bottom sill 24 and the facing pieces 55 and 56, is removable as a unit from the support wall 17 merely by the removal of the bolts or screws such as indicated at 35 and 38. This arrangement materially simplifies the assembly of the structure, and also permits ready removal of the closure frame from its support, as a structural unit, whereby to facilitate replacement, repair, et cetera.

The construction of the shade roller is best illustrated in Figs. 6, 10 and 11, the roller also being shown in Figs. 7, 8 and 12. Specifically the structure, generally indicated by the numeral 60, comprises a central shaft 61, a shade cylinder or roller 62, a pair of tape rollers 63 and 64, and a disc member 65 connected to the cylinder 62 by means of a screw 66. The shaft 61 is provided with reduced end portions, as shown in Fig. 6, for engagement with the slots in the end flanges of the roller frame top piece 37, one of these slots having been previously described and indicated at 45 in Fig. 3. The slots are preferably the same for either end of the roller, and provide journal bearings therefor, as well as to permit removal of the roller upon removal of the front plate 41, as previously set forth. The engagement of the ends of the shaft against the facing pieces 28 and 54, prevent endwise shifting of the shaft. The tape rollers 63 and 64 are fixed to the shaft 61, for example by means of set screws as indicated at 68 and 69, Fig. 6. On the other hand, the disc 65 is loosely mounted on the shaft 61 for relative rotation with respect thereto. It will thus be seen that the tape rollers 63 and 64 together with the shaft 61 form one integrally united unit, whereas the disc 65 and the shade roller or cylinder 62 constitute the second integral unit, relatively shiftable with respect to the shaft and the tape rollers. The ends of the cylinder 62 engage reduced inwardly extending projections on the tape rollers for support, but are journaled thereon for relative rotational movement. A coiled spring 70 loosely embraces shaft 61, and is anchored at one end to the disc 65 and at the other to the tape roller 64. When the parts are in assembled position, the spring applies a predetermined rotational tension, in opposite directions, to the disc 65 and the tape roller 64.

The cylinder 62 forms the support for the shade or closure member 72, and the means for anchoring the shade to the cylinder is best shown in Fig. 12. As illustrated, the looped end 73 of the shade is fitted through a slot 74 in the cylinder. A shaft 75 is then inserted through the end loop in the shade. This shaft is loose within the cylinder, but is of sufficient thickness so that it cannot be drawn through the slot 74. Accordingly, as tension is applied to the shade 72 the shaft may be drawn into engagement with the slot, as shown in Fig. 8, but it cannot be drawn therethrough and accordingly forms an anchorage structure. The shaft 75 passes through a slot 76 in the disc 65. The lower end of the shade is suitably formed

and stitched, as best shown in Fig. 8, so as to be anchored to a pair of cross bars 80 and 81. The cross bar 80 supports a handle member 82 at its central portion, the handle being secured to the bar by suitable means such as screws or the like; and the bar is further provided at each end with a guide member or block adapted to slide within the longitudinal slots of the side guiding columns. The guide block for the left column member is shown in perspective detail in Fig. 13, and the guiding arrangement is also illustrated in Figs. 6, 7 and 9. The guide means for each side of the shade are identical, and only one need be described.

Referring to Fig. 13, it will be seen that the guide block, indicated by the numeral 85, is provided with a pair of bifurcated portions 86 and 87 adapted to embrace the cross bar 80 and to be secured thereto by means of bolts or the like, as indicated in Fig. 9. The upper part of the guide block is of general T-shape in horizontal section, as will be best understood by reference to Figs. 9 and 13, whereby to conform to the shaping of the longitudinal slot or track 33 in the column. When the parts are in assembled position, the guide block cannot be withdrawn from the track, and the two guide blocks on either side of the shade cooperate to maintain the lower end thereof properly in position and against sidewise shifting. Each guide block has a friction shoe associated therewith engageable with the outer facing piece of the column, the friction shoe 90 associated with the left guide block 85 being illustrated in perspective detail in Fig. 14. A pair of compression springs 91 and 92, Fig. 6, apply a predetermined frictional pressure to the shoe against the facing member. These springs loosely embrace pins 93 and 94 formed on the shoe, and by means of which the shoe is loosely mounted on the guide block. It will be understood that the shoe is vertically movable as a unit with the guide block, but adapted for lateral shifting with respect thereto into frictional engagement with the facing member. In Fig. 6 the guide block and friction shoe for the right column are indicated by the numerals 95 and 96, respectively.

A tape member is arranged at each side of the structure, secured at one end to the guide block, and at its other end to the associated tape roller. Referring specifically to the tape structure for the left side of the shade, the tape, indicated by the numeral 100, is secured at its lower end to the guide block 85 by means of a screw and an associated metal clamp clip 101, as best shown in Fig. 7. The tape passes downwardly around the roller 53, previously described, thence upwardly to an idler guide roller 102, Figs. 6 and 7, and then wound around the tape roller 63 and anchored thereto by means of a screw and clamp clip assembly 103. The tape thus lies longitudinally within the column opening or track 33, and it will be noted, by reference to Figs. 7 and 8, that the tape and shade are oppositely wound at their upper ends. The tape member for the right side of the structure is indicated by the numeral 105 in Fig. 6.

A wiper or cleaner structure is arranged for cleaning the rear surface of the shade. The construction will be best understood by reference to Figs. 5 and 8. As shown, a shaft 106 is mounted within the roller frame structure, carried by the depending flanges such as indicated at 36, Fig. 3, of the top plate 37. The shaft carries a frame 107 upon which is mounted a cleaner or wiper

member 108. A pair of coiled springs 109 and 110, loosely mounted on the shaft 106, react against the frame 107 to urge the wiper into engagement with the shade roller. To provide anchorage for the springs, pins are carried by the top plate flanges, the pin for the left side of the structure being indicated at 111 in Figs. 7 and 8.

In the operation of the structure, it will be seen that the spring 70 constantly applies equal and opposite rotational forces to the disc 65 and the tape roller 64, which forces are transmitted to the upper end of the shade through the cylinder 62, and to the lower end thereof through the two integrally united tape rollers, and the associated tapes 100 and 105. The spring is so tensioned that it tends to produce counterclockwise rotation of the shade cylinder 62, as seen in Fig. 8, pulling upwardly on the upper end of the shade, and at the same time to produce clockwise rotation of the tape rollers, as seen in Fig. 7, thus tending to pull downwardly on the lower shade end. In other words, the shade is subjected to a predetermined stretching action at all times, holding it in position, and it will be noted that the magnitude of the stretching force remains substantially constant in all adjusted positions of the shade. At the same time the shade or closure member is maintained in balance, or subjected to equal and opposite operating forces, in all positions of adjustment so that there is no tendency on the part of the closure member to creep or move from adjusted position even though subjected to protracted periods of vibration, for example where used as a part of a railway vehicle or the like. As the shade is raised and lowered, the relative positions of the tape rollers 63 and 64 and the shade roller or cylinder 62 may be changed somewhat due to a difference in the thickness of the shade material with respect to that of the tapes, resulting in the building up of the tapes or the shade, as the case may be, upon the rollers at different rates. This produces a slight relative shifting of the spring coils, but inasmuch as the movement is small in relation to the overall capacity of the spring there will be no substantial change in the spring tension. However, the presence of the spring insures the maintenance of the shade in tight or stretched condition at all times and notwithstanding a difference in material thickness between the shade and the tapes.

The only resistance to movement of the shade is the action of the friction shoes 90 and 96, augmented slightly by the action of the wiper 108 and the friction of the various operating parts. It will be noted that this frictional resistance is substantially uniform in all of the shifted positions of the shade, and accordingly in the operation of the structure, to effect its movement, only the same predetermined operating force will invariably be required. Also, as stated, there is no tendency on the part of the spring 70 to cause creeping of the structure, either in raised or lowered position.

The guide blocks 85 and 95, in cooperation with the guide columns, maintain the lower end of the shade in proper position at all times, and provide efficient means for guiding the closure member in its movements. Also, the arrangement of the structure is such that any tendency to tilt or jam is minimized, and this is so regardless of which part of the lower shade end is gripped for manipulation. Assume, for example, that the extreme left edge of the shade is gripped and drawn downwardly. Under such circumstances

as the shade is pulled downwardly and the cylinder 62 rotated, overcoming the resistance of the spring 70, the spring remains operative to pull upon the tapes 100 and 105 with equal force to aid in the shade lowering movement. A similar action occurs on shade raising operations, wherein as either side edge of the shade is raised, the shaft 61 and integrally united tape rollers 63 and 64 are simultaneously released, permitting the spring 70 to exert a symmetrical lifting action through the cylinder 62 upon the shade element. In other words, during either lowering or raising operations, the spring 70 exerts symmetrical forces tending to induce movement of the shade, whereby to minimize jamming or tilting of the structure, no matter where it is gripped for operation.

It will be noted that the shade or closure member may be manipulated to the desired adjusted position merely by the application of the operating force thereto, manipulation of squeeze sticks or like levers being unnecessary. As the operating force is released, the movement of the closure member immediately and automatically stops, and thereafter there is no tendency for the closure member to creep or otherwise move from adjusted position. The tape members render the closure or shade self-aligning at all times, and the tapes in applying tension to the shade, maintaining it taut, preclude buckling or wrinkling, whereby to preclude jamming and excess wear. The guide blocks 85 and 95, fixed directly to the shade, are precluded from moving away from their guiding columns, thus further precluding jamming, avoiding improper operation, and also precluding rattling and insuring silent operation.

It will further be noted that the edge of the shade extends into the guide tracks or slots, such as the slot 33, formed in the guide columns. The slot portion into which the shade projects, as well as the central portion of the slot 43 through which the shade projects at its upper end, is relatively narrow, and an arrangement is thereby produced rendering the shade or closure member light-tight and efficient in operation.

Each time the structure is operated, the wiper 108 effects an automatic cleaning operation upon the rear shade surface which may, in most installations, be inaccessible. The front surface of the shade may be readily cleaned when the shade is in lowered position.

As previously indicated, the entire shade frame 16 is removable as a unit from the support structure 17, whereby to facilitate assembly of the parts, and also permit replacement, substitution and repair. As also previously indicated, the closure may be either vertically or horizontally operable, or may, if desired, be so arranged that the roller structure is at the bottom, the shade member being drawn or moved upwardly therefrom. The shade or closure member may also, if desired, be power operated, rather than by manual force, and it is to be understood that the closure member may take the form of a Venetian blind, rolling door, fire door, theater curtain, sliding partition, folding or rolling panel, flexible or rigid curtain, et cetera, of fabric, wood or metal materials.

It is obvious that various changes may be made in the specific embodiments of the invention set forth for purposes of illustration without departing from the spirit thereof. Accordingly the invention is not to be limited to the specific embodiments set forth and described, but only as indicated in the following claims.

The invention is hereby claimed as follows:

1. A closure structure comprising a closure member adapted to be drawn across an opening to be closed, said closure member being slidably shiftable in opposite directions of travel, means positively connected to opposite sides of the closure member at one end operable to urge the closure member in one direction of travel with a predetermined force, means positively connected to opposite sides of the closure member at its other end simultaneously operable to urge the closure member in the opposite direction of travel with the same predetermined force, a pair of frame members adjacent the opposite sides of the closure member along which one end of the closure member is adapted to be slidably shifted, and friction means between the frame members and the sides of the closure member at said latter end for yieldably resisting movement thereof.
2. A closure structure comprising a closure member adapted to be drawn across an opening to be closed, said closure member being slidably shiftable in opposite direction of travel, spring means positively connected to opposite sides of the closure member at one end continuously operable to urge the closure member in one direction of travel with a predetermined force, spring means positively connected to opposite sides of the closure member at its other end continuously operable to urge the closure member in the opposite direction of travel with the same predetermined force, said spring means being operable in all positions of adjustment of the closure member, a pair of guide tracks adjacent the opposite side of the closure member arranged to guide one end of the closure member in its shiftable movements, and friction means between the guide tracks and the sides of the closure member at said latter end for yieldably resisting movement thereof.
3. A closure structure comprising a closure member adapted to be drawn across an opening to be closed, said closure member being slidably shiftable in opposite directions of travel, spring means positively connected to opposite sides of the closure member at one point along the length thereof operable upon the closure member in any position of adjustment to urge the closure member in one direction of travel with a predetermined force, said spring means being also positively connected to opposite sides of the closure member at another point along the length thereof to simultaneously urge the closure member in the opposite direction of travel with the same predetermined force, the force of said spring means being the same in all positions of adjustment of the closure member, a pair of frame members adjacent the opposite sides of the closure member along which one end of the closure member is adapted to be slidably shifted, and friction means between the frame members and the sides of the closure member at said latter end for yieldably resisting movement thereof.
4. A closure structure comprising a closure member adapted to be drawn across an opening to be closed, said closure member being slidably shiftable in opposite directions of travel, a roller structure comprising a pair of rotatable elements, means operatively connecting one of said rotatable elements to the closure member at one point along the length thereof and symmetrically with respect to the line of shift of the closure member for shifting the closure member in one direction when the rotatable element is rotated in a given direction of travel, means operatively connecting

the other rotatable element to the closure member at another point along the length thereof and symmetrically with respect to the line of shift of the closure member for shifting the closure member in the opposite direction when said element is rotated in a given direction of travel, a single spring operatively connecting said rotatable elements for urging them in said given directions of travel whereby said elements supply equal and opposite symmetrically applied forces to the closure member, a pair of frame members adjacent the opposite sides of the closure member along which one end of the closure member is adapted to be slidably shifted, and friction means between the frame members and the sides of the closure member at said latter end for yieldably resisting movement thereof.

5. A closure structure comprising a closure member adapted to be drawn across an opening to be closed, said closure member being slidably shiftable in opposite directions of travel, a roller structure comprising two sets of relatively rotatable elements, means operatively connecting one set of said elements to the closure member for shifting the closure member in one direction when said set of elements is rotated in a given direction of rotation, means operatively connecting the other set of rotatable elements to the closure member for shifting the closure member in the opposite direction when said set of elements is rotated in a given direction of rotation, said last named connecting means comprising a pair of elongated flexible members connected at one end to opposite sides of the closure member and at the other end to said other set of rotatable elements, guide means over which said elongated members are substantially reversely bent intermediate their ends, a single spring operatively connecting said sets of rotatable elements for urging them in said given direction of rotation, a pair of guide tracks adjacent the opposite sides of the closure member arranged to guide one end of the closure member in its shiftable movements, and friction means between the guide tracks and the sides of the closure member at said latter end for yieldably resisting movement thereof.

6. A shade structure comprising a shade member adapted to be drawn across an opening to be closed, said shade member being slidably shiftable in opposite directions of travel, a roller structure comprising a rotatable cylinder and a roller element arranged at each end thereof, means connecting one end of the shade member to the rotatable cylinder, a pair of tape members connecting the opposite sides of the other end of the shade member to said roller element, guide means over which the tape members are substantially reversely bent intermediate their ends, a spring for continuously applying force to the rotatable cylinder and both the roller elements whereby to urge the ends of the shade in opposite directions away from the shade body, a pair of guide tracks adjacent the opposite sides of the shade arranged to guide one end of the shade in its shiftable movements, and spring pressed friction shoes between the guide tracks and the

sides of the shade at said latter end for yieldably resisting movement thereof.

7. A shade structure comprising a shade member adapted to be drawn across an opening to be closed, said shade member being slidably shiftable in opposite directions of travel, a shade cylinder upon which one end of the shade is adapted to be wound, a roller arranged at each end of the shade cylinder upon which the cylinder ends are rotatably supported, tape members secured to the rollers and to the other end of the shade at opposite side edges thereof, guide means for the tape members over which the tape members are substantially reversely bent intermediate their ends, a single spring connected to the shade cylinder and to both said rollers for urging them in opposite directions of rotation, a rectangular sub-frame adapted to be applied as a unit to a main frame opening to be closed, said sub-frame comprising a pair of guide tracks adjacent the opposite sides of the shade member arranged to guide one end of the shade member in its shiftable movements, and spring pressed friction shoes between the guide tracks and the sides of the shade member at said latter end and yieldably resisting movement thereof.

8. A shade structure comprising a shade member adapted to be drawn across an opening to be closed, said shade member being slidably shiftable in opposite directions of travel, a shade cylinder upon which the upper end of the shade is adapted to be wound, a roller arranged at each end of said cylinder, tapes operatively connected to said rollers and to the lower end of the shade at opposite sides thereof, guide means over which the tapes are substantially reversely bent intermediate their ends, a spring positively connected to said shade cylinder and both said rollers for urging the shade cylinder and rollers in opposite directions of rotation, columns arranged at each side of the shade, said columns being provided with guide tracks along the path of travel of the shade, guide blocks secured to the lower end of the shade at opposite sides thereof and adapted for sliding movement along said guide tracks and resilient means for urging the guide blocks against the guide tracks with a predetermined force whereby to yieldably resist movement of the shade member.

9. A closure structure comprising a closure member adapted to be moved across an opening to be closed, said closure member being slidably shiftable in opposite directions of travel, a rectangular frame for supporting the closure member, control mechanism carried by the frame for controlling the movements of the closure member, guide means carried by the frame for guiding the movements of the closure member, and a support structure for supporting the frame, said frame, closure member, control means, and guide means being secured together as a self-contained unit and being removably attached to said support whereby to be removable as a unit therefrom.
